UNITED STATES PATENT OFFICE

JESSIE JACKSON ROBERTS, OF DOUGLASVILLE, GEORGIA, ASSIGNOR TO DRAPER CORPORATION, OF HOPEDALE, MASSACHUSETTS, A CORPORATION OF MAINE

LOOM TEMPLE

Application filed September 25, 1930. Serial No. 484,299.

This invention relates to loom temples and is more particularly directed to means for yieldingly balancing the temple rod and cloth engaging means against the lateral pull of the fabric during weaving.

During the weaving operation there is a natural tendency for the cloth to contract in width and to counteract such tendency loom temples have been heretofore arranged, one at each side of the cloth, adjacent the weaving point. As well understood in the art, the temple rod or shank and the cloth engaging member are mounted upon a temple stand with relation to which said parts have a movement towards and from the front of the loom. Such recurring movements, however, produce excessive wear between the temple stand and the temple rod or shank, with the result that the temples will not act effectively upon the cloth. In some cases, also, where the cloth engaging member of the temple is below the plane of movement of the temple rod or shank, such excessive wear is liable to cause the temple engaging member to be tilted with respect to the plane of the cloth.

These facts have heretofore been well understood and means have been provided in an attempt to prevent such excessive wear and improper action of the temples, but with the constructions heretofore known the objectionable wear between the parts soon permits the temples to yield laterally towards each other under the pull of the cloth, and an important feature of the present invention therefore consists in providing means to act yieldingly in a lateral direction and in opposition to the cloth pull to insure that even with the occurrence of wear in the temple parts the temple engaging members will exert a lateral stress in opposition to the natural tendency of the cloth to contract widthwise.

The invention and new features thereof will best be made clear from the following description and the accompanying drawings of one good form thereof.

In the drawings:

Fig. 1 is a plan view showing parts of a loom and temples provided with the present invention;

Fig. 2 is an enlarged perspective view of

a temple containing the present invention; and

Fig. 3 is a side view of the temple looking in the direction opposite to that of Fig. 2.

Inasmuch as the temples at each side of the cloth may be of substantially the same construction and embody the present invention, a description of one of such temples will be sufficient.

The loom frame 1 may be of usual construction and extending laterally between the side frames of the loom is the breast beam 2 on which the temples may be mounted in any suitable manner as now well understood in the art.

The lay 3 may also be of usual construction and extending frontwardly over the race of the lay are the warp threads *a* which, at the weaving point, are associated with suitable weft or filling threads to form the cloth *b*.

Each of the temples consists of a temple stand 4 in which is mounted for sliding movement towards and from the front of the loom the temple rod or shank 5. The temple stand may be of any usual construction but as herein shown is of the usual box-like form, and within the temple stand is a spring 6 normally acting to move the temple rod or shank 5 rearwardly with permissive frontward movement. Extending laterally from the temple head 7 is the temple top or cap 8 in which is mounted the cloth engaging member 9 which may be of any usual character but herein shown as a pin roller, the pins of which engage the cloth and serve to maintain it in lateral position against the pull of the cloth.

Extending downwardly from the temple head 7 is the finger 10 adapted to be engaged by the lay or a part carried thereby as the lay moves frontwardly, to thereby effect frontward movement of the temple engaging member and the temple rod or shank 5.

In the present illustration of the invention the temple is indicated as provided with a thread cutter 11 which may be operated by an actuating member 12 as the lay moves frontwardly. All of the parts as thus far described may be and are as of usual con-

struction and it will be understood therefrom that the cloth will exert a lateral pull upon the temples at each side thereof during the weaving operation as the cloth tends to contract.

It is essential, however, that the cloth be prevented from contracting widthwise, and in accordance with the present invention a yielding member is associated with the temple rod or shank 5 to exert a yielding lateral stress upon the temples in opposition to the pull of the cloth.

In accordance with the present embodiment of the invention the yielding member for acting as described is secured to the temple rod or shank 5 and has its front portion bearing upon the temple stand, with the result that not only is the cloth maintained under yielding stress against its natural tendency to contract, but the engaging parts between the temple stand and temple rod or shank 5 are prevented from undesirable wear.

The temple rod or shank 5 is provided with a shouldered portion 13, Fig. 2, on which rests the rear end portion of the temple balancing or spring member 14 which may be secured to the temple rod or shank 5 by means of a bolt 15 or other suitable means. The temple balancing member is herein shown as a leaf spring 16 which is secured at its rear portion to the temple rod or shank 5, with its free front portion 17 bearing against the side of the temple stand 4. Between the two ends of the leaf spring the latter is bent outwardly, as at 18, to thereby impart to the free front end portion of the spring an increased spring action tending to move the temple rod or shank 5 and the cloth engaging member 9 laterally in opposition to the pull of the cloth as the cloth engaging member and temple rod or shank are moved frontwardly during the weaving operation.

In some cases it may be desirable to provide the free end of the leaf spring 16 with openings 19 to modify to some extent the resilient action of the spring.

During the weaving operation, the lay will engage the cutter actuator 12 to operate the cutter and then will similarly engage the finger 10 extending from the temple head, with the result that the temple rod or shank 5 and the cloth engaging member 9 will be moved frontwardly against the action of the spring 6. At such times the free end 17 of the leaf spring will ride along the side of the temple stand and exert a lateral stress upon the temple outwardly or in opposition to the pull of the cloth, thereby maintaining the cloth in the desired widthwise stretch under yielding action and at the same time prevent undue wear between the temple stand and the temple rod or shank 5.

In those cases wherein the temple cutter is employed, the cutter is usually maintained in its inactive position by means of a spring 20,

herein shown as passing about a spring holder or bolt 21 extending laterally from the temple rod or shank 5 with its limb 22 in engagement with a pin 23 extending from the actuator 12. Where such temple cutter is employed, the present invention provides a convenient and effective means for securing the opposite end of the spring 20 in fixed position on the temple rod or shank 5, and as shown it will be noted that the end 24 of the spring 20 extends into a recess between the shoulder 13 formed on the temple rod or shank 5 and the end portion of the spring 16.

In accordance with the present invention as herein shown and described it will be noted that the cloth is continuously subjected to a yielding lateral stress in opposition to the natural tendency of the cloth to contract widthwise during weaving and that the lateral stress thus placed upon the cloth engaging member and temple rod or shank 5 prevents undue wear between the parts of the temple stand and the temple rod or shank.

What is claimed is:

1. A loom temple comprising a temple stand, a temple rod or shank mounted for longitudinal sliding movement on the temple stand, and a flexible member secured to the temple rod or shank rearward of the temple stand and having sliding engagement against the exterior of the temple stand to automatically exert a yieldable lateral stress on the temple rod or shank in opposition to the lateral pull of the fabric during weaving.

2. In a loom temple, the combination of the temple stand, a temple rod or shank mounted for sliding movement on the temple stand, a cloth engaging member carried by the temple rod or shank, a flexible member connected to the temple rod or shank rearward of the temple stand and having a frontward extension bearing upon the exterior of the temple stand to automatically exert a lateral yielding stress on the temple rod or shank in opposition to the lateral pull of the cloth during weaving.

3. In a loom temple, the combination of the temple stand, a temple rod or shank mounted for sliding movement on the temple stand, a cloth engaging member carried by the temple rod or shank, a leaf spring having one end secured to the temple rod or shank rearward of the temple stand and its free end portion in sliding engagement with a fixed part exterior of the temple stand to yieldingly resist the lateral pull of the cloth during weaving as the temple rod or shank is moved towards and from the front of the loom.

4. In a loom temple, the combination of a temple stand, a temple rod or shank mounted for sliding movement in the temple stand, a cloth engaging member carried by the temple rod or shank, a leaf spring having one end secured to the temple rod or shank ad-

jacent to the cloth engaging member and its free end extending forwardly into sliding engagement with the side of the temple stand to exert a yielding lateral stress upon the temple rod or shank in opposition to the lateral pull of the cloth as the temple rod or shank moves towards and from the front of the loom during weaving.

5. In a loom temple, the combination of
10 the temple stand, a temple rod or shank mounted for sliding movement in the temple stand and having a cloth engaging member, a shoulder formed on the temple rod or shank forward of the cloth engaging member, a
15 leaf spring having its rear end portion bearing upon said shoulder, means for securing the leaf spring to the temple rod or shank with its free front portion bearing yielding-
20 ly upon the temple stand to exert a yielding stress upon the temple rod or shank and cloth engaging member in opposition to the lateral pull of the cloth during weaving.

6. In a loom temple, the combination of
25 the temple stand, a temple rod or shank having a cloth engaging member, a leaf spring having its rear end portion secured to the temple rod or shank rearward of the temple stand and formed with a bend forward of its rear end with the free end of the spring
30 frontward of a fixed surface exterior of the bend resting against the temple stand and exerting a lateral yielding stress upon the temple rod or shank and the cloth engaging member in opposition to the inward pull of
35 the cloth during weaving.

In testimony whereof, I have signed my name to this specification.

JESSIE JACKSON ROBERTS.
